1 Claim

ABSTRACT OF THE DISCLOSURE

An oxide magnet consisting primarily of BaO and Fe_2O_3 , the molar ratio of BaO to Fe_2O_3 being between 1:5 and 1:6, and containing in addition 0.05 to 0.3% by weight CaO and 0.4 to 0.65% by weight of SiO_2 , has large coercive force and high magnetic energy.

This invention relates to improvements in oxide magnet materials, particularly to improvements in oxide magnet materials having magnetoplumbite crystal structure composed of $Mo.6Fe_2O_3$ where M is a metal selected from the group consisting of Ba, Sr and Pb.

It is well-known that the oxide magnet composed of BaO₆FeO has good magnetic properties, that is, its coercive force B^{H_c} is large and its magnetic energy $(BH)_{max}$ is higher than that of the cobalt ferrite magnet. The magnetic remanence Br of BaO₆Fe₂O₃ is however, not satisfactorily large, and though various improvements were proposed, this defect has not been overcome.

It is, therefore, the object of this invention to improve the magnetic properties of the binary system comprising MO and Fe_2O_3 . More fully speaking, the object of this invention is to improve Br, B^{H_c} and $(BH)_{max}$ of the magnet of above-mentioned binary system, where the molar ratio of Fe_2O_3 to MO is between 5 to 6, by adding small quantities of CaO and SiO_2 .

This invention may be more readily understood by reference to the following detailed description and to the accompanying drawings, in which:

FIGS. 1 and 4 show curves indicating magnetic properties of oxide magnets of this invention;

FIG. 2 shows curves of magnetic properties of oxide magnets wherein CaO only has been added;

FIG. 3 shows curves of magnetic properties of oxide magnets in which SiO_2 only has been added;

FIG. 5 shows curves of $(BH)_{max}$ of oxide magnets BaO_nFe₂O₃, where n is between 5 and 6, containing in addition both SiO_2 and CaO; and

FIG. 6 shows curves of H_c of the same magnets given in FIG. 5.

Briefly stated, according to the present invention, a novel composition of oxide magnet materials with specific compositional ratios is obtained, so that the magnetic properties of the magnet are considerably improved. The method of producing it, however, is not substantially different from that of the prior art, and as such it does not constitute part of the invention.

The following is an example of the magnet of the invention:

A mixture of metallic oxides in the molar proportions 5.3 Fe_2O_3 and 1.0 BaO is intimately mixed, presintered and crushed, and then the crushed mixture of materials is combined with about 0.1% by weight of CaO and about 0.4 to about 0.8% by weight of SiO_2 , and sintered at about 1200° C. The resulting sintered oxides have the following magnetic properties:

SiO_2/CaO	0	0.4/0.1	0.5/0.1	0.6/0.1	0.7/0.1	0.8/0.1
Br (gauss)	1,890	2,240	2,340	2,260	2,180	2,100
H_c (oe.)	1,840	2,080	2,149	2,180	2,100	2,020
$(BH)_{max}$	0.87	1.12	1.25	1.23	1.14	1.06

2

FIG. 1 gives the curves illustrating the abovementioned characteristics.

For purpose of comparison, either CaO or SiO_2 alone is added to the BaO mixture of $(Fe_2O_3)=5.3$. These mixtures were also sintered at 1200° C. In these cases, the variation of the properties of magnets as a function of the proportion of CaO or SiO_2 is as follows:

CaO(wt. percent)	0	0.05	0.1	0.2	0.35	1.0
Br (gauss)	1,890	1,920	2,040	2,040	2,020	2,000
H_c (oe.)	1,840	1,890	1,970	1,990	1,970	1,800
$(BH)_{max}$	0.87	0.91	1.00	1.01	0.99	0.9

SiO ₂ (wt. percent)	0	0.2	0.4	0.7	1.0	2.0
Br (gauss)	1,890	2,180	2,170	2,130	2,140	2,060
H_c (oe.)	1,840	2,120	2,130	2,100	2,040	2,010
$(BH)_{max}$	0.87	1.15	1.15	1.12	1.09	1.04
CaO(wt. percent)	0	0.05	0.1	0.2	0.35	1.0

FIGS. 2 and 3 show the curves illustrating the abovementioned characteristics.

It is clear from the above comparative tables that the magnetic properties of the material $(BaO.nFe_2O_3)$ mixed together with both CaO and SiO_2 are far better than those of the material mixed with only one of either CaO or SiO_2 .

The variation of the magnetic properties of the material as a function of the proportions of CaO and SiO_2 may be given as follows (wherein the fundamental composition is BaO₅(Fe_2O_3)5.3):

SiO_2/CaO (molar ratio)	0.2/0.5	0.35/0.35	0.5/0.2	0.6/0.1	0.65/0.05	0.7/0
Br (gauss)	2,020	2,200	2,280	2,260	2,230	2,130
H_c (oe.)	1,950	2,040	2,180	2,180	2,110	2,100
$(BH)_{max}$	0.98	1.12	1.25	1.23	1.17	1.12

FIG. 4 shows the curves illustrating the abovementioned characteristics.

As shown in FIGS. 1 and 4, although the Br, H_c and $(BH)_{max}$ of BaO₅(Fe_2O_3)5.3 are 1890 (gauss), 1840 (oe.) and 0.87×10^6 , respectively, these properties are improved by more than 10% if both CaO and SiO_2 are added to said oxide magnet material. And moreover, experimental tests clearly teach that the density of the oxide magnet increases by more than 10% by addition of these two oxides.

The magnetic properties of the oxide magnet

BaO(Fe_2O_3)_n

where n is between 5.0 and 6.0, containing 0.6 weight percent of SiO_2 and 0.1 weight percent of CaO are as follows:

Ratio of Fe_2O_3 to BaO	5.0	5.3	5.6	6.0
(a) Nothing being added:				
Br	1,910	1,890	1,710	1,520
H_c	1,940	1,840	1,750	1,500
$(BH)_{max}$	0.89	0.87	0.75	0.57
(b) 0.6 wt. percent of SiO_2 and 0.1 wt. percent of CaO being added:				
Br	2,140	2,260	2,220	1,980
H_c	2,200	2,180	2,170	2,080
$(BH)_{max}$	1.17	1.23	1.16	1.02

The curve A₁ of FIG. 5 shows the Br of the material containing 0.6% by weight of SiO_2 and 0.1% by weight of CaO, while the curve B₁ shows the Br of the material containing neither SiO_2 nor CaO.

In FIG. 6, the curves A₂ and B₂ show the H_c of the materials containing both, and containing neither, respectively, SiO_2 and CaO.

Curves C and D of FIG. 5 show the magnetic energy $(BH)_{max}$ of the materials with the same above-mentioned compositions.

It is clear from FIGS. 5 and 6 that the addition of CaO and SiO₂ is very effective for the improvement of the magnetic properties of the oxide material

As it can be readily understood from the foregoing description, the magnetic properties of the oxide magnet composed of Fe₂O₃ and BaO, the ratio of Fe₂O₃ to BaO being between 5.0 and 6.0, are much improved by the addition of 0.05 to 0.3% by weight of CaO and 0.4 to 10 0.65% by weight of SiO₂, the result being a magnet having a large coercive force and a high magnetic remanence.

The proportions of the oxides, when limited to the above-mentioned ranges give the maximum values of Br, H_c and (BH)_{max} within said range.

What we claim as new and wish to secure by Letters Patent of the United States is:

1. A barium ferrite magnet in which BaO and Fe₂O₃ are in a molar ratio of BaO to Fe₂O₃ of between 1:5 and

1:6 and wherein there are present from about 0.05 to about 0.3% by weight of CaO and from about 0.4 to about 0.65% by weight of SiO₂.
